UNITED STATES PATENT OFFICE.

EBENEZER BLACKMAN, OF BROOKLYN, NEW YORK.

SHADE FOR LAMPS.

SPECIFICATION forming part of Letters Patent No. 247,600, dated September 27, 1881.

Application filed June 23, 1881. (No model.)

To all whom it may concern:

Be it known that I, EBENEZER BLACKMAN, of Brooklyn, in Kings county, and State of New York, have invented certain new and useful Improvements in Shades for Lamps, of which the following is a specification.

It is common to employ in connection with lamps and other illuminating apparatus shades supported on shade-holders at some distance above the burners from which the light emanates. While these shades are sufficient for ordinary purposes, it oftentimes happens that it is desirable to provide some protection to the eyes from the direct rays of light passing outward below the shades or to deflect those rays downward.

It is an important object of my present improvements to provide for this.

To this end my invention consists in the combination, with a shade and shade-holder, of a supplemental shade made independent thereof and detachably supported thereby, so as to afford protection from direct rays of light passing outward below the shade and deflect them downward. This supplemental shade may be supported on the shade, on the shade-holder, or between the two.

My improvements also consist in a supplemental shade of the kind and for the purposes mentioned, as a new article of manufacture.

In the accompanying drawings, Figure 1 is a side view of a lamp-burner and a vertical section of a shade-holder, a shade, and a supplemental shade embodying my improvements. Fig. 2 is an inverted plan of the supplemental shade, and Fig. 3 is a section of the upper edge portion of the supplemental shade upon a larger scale.

Similar letters of reference designate corresponding parts in all the figures.

A designates a lamp-burner, which may be of any desirable form.

B designates a shade-holder made of glass, and fitting on the gallery of the lamp-burner A within spring-arms, with which it is provided.

C designates a shade of opal glass, supported by the shade-holder B and fitting within its upper portion.

D designates an independent supplemental shade, made of paper or other suitable material and in the form of a hollow frustum of a

cone. As shown, its upper edge is bent inward and downward, so as to hook or extend over and inside the upper edge of the shade-holder B and fit between it and the lower portion of the shade C. When thus combined with the shade-holder and shade it forms a packing between them, preventing them from rattling when any vibrations or tremors are imparted to them and precluding air from entering between them to affect the flame issuing from the lamp-burner A. To the inner surface, and preferably, also, to the outer surface, of the upper portion of this supplemental shade is applied a coating of soluble glass. This is indicated in Fig. 1 by an extra thickness of the lines, and in Fig. 2 by a series of concentric lines.

In Fig. 3 the outer and inner coatings of soluble glass are respectively designated by the letters D' D''. The soluble glass will protect the surface of the supplemental shade from moisture, and will serve as a good non-conductor to prevent heat from being transmitted from the shade C to the shade-holder B. The supplemental shade D, without the coating of soluble glass, would measurably serve the same purpose when combined with the said shade and shade-holder, as shown. This is an important function, as the danger of cracking the shade-holder is thereby lessened.

The supplemental shade may simply have its upper edge bent inward horizontally and fitted between the upper edge of the shade-holder B and the shoulder *a* of the shade C. It may have its edge so bent as to fit upon the shoulder or bead *b* of the shade-holder B. If desirable, it may even be adapted to be slipped over and supported on the shade C.

It is obvious that my supplemental shade may be similarly used in connection with metal shade-holders as well as the glass shade-holder above described. Such supplemental shade may be applied to existing lamps, and may be used when desired and removed at other times.

The supplemental shade-holder will prove advantageous in confining air and directing it to the lamp-burner.

What I claim as my invention, and desire to secure by Letters Patent, is—

1. The combination, with a shade and shade-holder, of a supplemental shade made independent thereof and detachably supported

thereby, so as to afford protection from direct rays of light passing outward below the shade and deflect them downward, substantially as specified.

5. The combination, with a shade and shade-holder, of a supplemental shade having its upper edge fitted between the two and supported by them, substantially as specified.

6. The combination, with a shade and a glass shade-holder, of a supplemental shade having its upper edge bent over and inside the shade-holder, so as to fit between it and the shade, substantially as specified.

7. As a new article of manufacture, a supplemental shade adapted at its top to fit between a shade and shade-holder and be supported thereby, and to extend below the shade and afford protection from the direct rays of light passing outward below the shade and deflect them downward, substantially as specified.

E. BLACKMAN.
